GROUND CLAMP

Daly P. Andrews and Benjamin D. Heeger,
Mountain Grove, Mo.

Application December 23, 1942, Serial No. 469,954

5 Claims. (Cl. 24—263)

This invention relates to a ground clamp and has relation more particularly to a clamp of this kind especially designed and adapted to use in connection with electric welding, and it is a particular object of the invention to provide a clamp of this kind whereby the ground cable used in electric welding is of a character to eliminate leakage and poor connections, particularly when the clamp is engaged on rusty or scaly steel or dirty metal.

Another object of the invention is to provide a clamp which can be employed with equal facility in connection with work of varying thickness within a certain range and wherein the clamp, while particularly designed as a ground clamp, may be used for other purposes when desired.

The invention consists in the details of construction and in the combination and arrangement of the several parts of our improved ground clamp whereby certain important advantages are attained, as will be hereinafter more fully set forth.

In order that our invention may be the better understood, we will now proceed to describe the same with reference to the accompanying drawing, wherein—

Figure 1 is a view in side elevation of a clamp constructed in accordance with an embodiment of our invention, a second position of one of the parts being indicated by broken lines; and

Figure 2 is a view in top plan of the device as illustrated in Figure 1.

As disclosed in the accompanying drawing, 1 denotes an elongated base member of desired dimensions and which is continued at one end by an outwardly disposed extension 2 terminating in an inwardly curved arm 3. This arm 3 at its free end carries a jaw 4 of desired dimensions and which jaw may be as preferred. The rear end of the member 1, or that end portion remote from the jaw 4, is continued by an outwardly disposed arm 5 which constitutes a hand grip. The central portion of the base member 1 rigidly carries a perpendicularly related post 6 herein disclosed as rectangular in cross-section. This post is of material length, and having contact with the forward face *a* of this post 6 is a relatively long flat face *b* at the inner or rear end of an elongated arm 7. This arm 7 is provided at its forward extremity with a jaw 8 for coaction with the jaw 4. The arm 7, as illustrated in Fig. 1, is outwardly curved as may be preferred and the rear end portion of the arm 7 is laterally enlarged, as at 9, to allow the face *b* to be of considerable length to assure the

desired frictional contact between the faces *a* and *b*.

In the present embodiment of the invention the face *b* is on a plate or lay 10 of brass welded, brazed or otherwise rigidly secured to the adjacent end proper of the arm 7.

Secured by the screws 11 or the like to the opposite side faces of the rear or enlarger portion 9 of the arm 7 are the corresponding legs 12 of the substantially U-shaped spring members M. As is clearly illustrated in Figure 1, the connection of each of the legs 12 with the arm 7 is rigid so that there will be no swinging movement of a spring member M with respect to the arm 7. Each of these spring members M has its intermediate or base portion 14 extending across a side face of the post 6 and, as is clearly illustrated in Figure 1, the second or rear leg 15 on each of the spring members M is shorter than the length of the leg 12. The free end portion of the leg 15 of each of the spring members M is secured by a screw 16 or the like to the side face of a head 17 carried by the inner extremity of a lever 18 which is in proximity to the hand grip 5. The head 17 is provided in its upper or outer portion with a flat face 19 which, when the lever 18 is swung away from the hand grip 5 as illustrated by broken lines in Figure 1, will closely approach the rear edge face of the post 6 and allow the arm 7 to be shifted or adjusted lengthwise of the post 6 as may be desired and as may be required by the thickness of the plate or other work to be gripped between the jaws 4 or 8. This face 19 of the head 17, as herein disclosed, is on an angle of approximately 45° with respect to the longitudinal axis of the lever 18, and the portion of the head 17 immediately below the forward or lower end of the face 19 is formed to provide an inbow face 20 which results in the provision of the fingers or lugs 21 which serve as fulcrums to allow the convenient swinging or rocking of the lever 18 as desired. It is to be pointed out that the spring members M serve to maintain the rear portion 9 of the arm 7 and the head 17 of the lever 18 in tight contact with the post 6, yet said springs will sufficiently yield to allow the desired swinging or rocking of the lever 18 to assure desired clamping action of the jaws 4 or to allow the desired adjustment of the arm 7 lengthwise of the post 6.

The post 6, at a desired point intermediate its ends, has extending outwardly from its side faces the stop pins 22 with which contact the

intermediate portions 14 of the spring members M, and thus limit the extent of outward movement of the arm 7 and the lever 18 along the post 6.

The adjacent portions of the base member 1 and the extension 2 are outwardly enlarged to provide a lug or block 21. This lug or block 21 is provided with a socket 22 facing or opening inwardly of the base member 1. This socket 22 is adapted to have inserted therein an extremity of a ground cable, and said applied cable will be effectively held to the lug or block 21 by a binding screw 23 threading into said lug or block. It is believed to be obvious, however, that if preferred the ground cable may be fastened within the socket 22 by soldering.

From the foregoing description it is thought to be obvious that a ground clamp constructed in accordance with our invention is particularly well adapted for use by reason of the convenience and facility with which it may be assembled and operated.

We claim:

1. A clamp of the class described comprising an elongated member, a jaw carried by said member, a post carried by and extending laterally from the member, an elongated arm having a rear face for contact with a face of the post, a lever at the rear of the post, spring means connecting the rear portion of the arm and the lever for maintaining the arm and lever in close contact with the post, and a jaw carried by the arm for coaction with the jaw of the member, the lever having a fulcrum lug for direct contact with the adjacent face of the post.

2. A clamp of the class described comprising an elongated member, a jaw carried by said member, a post carried by and extending laterally from the member, an elongated arm having a rear face for contact with a face of the post, a lever at the rear of the post, spring means connecting the rear portion of the arm and the lever for maintaining the arm and lever in close contact with the post, a jaw carried by the arm for coaction with the jaw of the member, the lever having a fulcrum lug for direct contact with the adjacent face of the post, and means for limiting the movement of the arm and lever outwardly along the post.

3. A clamp of the class described comprising an elongated member, a jaw carried by said member, a post extending laterally from said member, an arm having a rear face contacting with a face of the post, a jaw carried by the arm for coaction with the jaw of the member, spring members secured to the rear portions of the arm and extending across and rearwardly of the post, a lever, means for securing the spring members to the lever, said spring members operating to normally maintain the rear face of the arm, and the lever in close contact with the post, the post having a fulcrum lug for direct contact with the post.

4. A clamp of the class described comprising an elongated member, a jaw carried by said member, a post extending laterally from said member, an arm having a rear face contacting with a face of the post, a jaw carried by the arm for coaction with the jaw of the member, spring members secured to the rear portions of the arm and extending across and rearwardly of the post, a lever, means for securing the spring members to the lever, said spring members operating to normally maintain the rear face of the arm, and the lever in close contact with the post, the post having a fulcrum lug for direct contact with the post, each of the spring members being substantially U-shaped in form.

5. A clamp of the class described comprising an elongated member, a jaw carried by said member, a post extending laterally from said member, an arm having a rear face contacting with a face of the post, a jaw carried by the arm for coaction with the jaw of the member, spring members secured to the rear portions of the arm and extending across and rearwardly of the post, a lever, means for securing the spring members to the lever, said spring members operating to normally maintain the rear face of the arm and the lever in close contact with the post, the post having a fulcrum lug for direct contact with the post, each of the spring members being substantially U-shaped in form, and means carried by the post for contact with the intermediate portion of the spring members for limiting the movement of the arm and the lever outwardly of the post.
